DESIGN FOR A DUMP BODY TRUCK

Charles G. Eisenberg, Jr., Wauwatosa, Wis., assignor to The Heil Co., Milwaukee, Wis., a corporation of Wisconsin

Application September 29, 1934, Serial No. 53,432

Term of patent 14 years

To all whom it may concern:

Be it known that I, Charles G. Eisenberg, Jr., a citizen of the United States, residing at Wauwatosa, in the county of Milwaukee and State of Wisconsin, have invented a new, original, and ornamental Design for a Dump Body Truck, of which the following is a description, reference being had to the accompanying drawing, forming part thereof.

In the drawing:

Fig. 1 is a side elevation of the completed truck;

Fig. 2 is a rear view of the completed truck; and

Fig. 3 is a top view of the dump body, showing my new design.

The dominant or important features of the design are shown in solid lines, and the immaterial features are shown in dotted lines.

I claim:

The ornamental design for a dump body truck, substantially as shown and described.

CHARLES G. EISENBERG, JR.
